GASKET

Leonard H. Darbyshire, Detroit, Mich., assignor,
by mesne assignments, to Borg-Warner Corporation,
a corporation of Illinois

Original application August 8, 1932, Serial No.
627,865. Divided and this application August
13, 1934, Serial No. 739,611

3 Claims. (Cl. 62—89)

This application is a division of an application for "Gasket" filed August 8, 1932, and bearing Serial Number 627,865, which has matured into Patent No. 1,995,379.

5 This invention relates to freezer construction for mechanical refrigerators and has special reference to the elimination of air circulation into a quick freezing compartment used for the production of ice cubes and frozen desserts.

10 I have found that when air circulation is permitted into the quick freezing compartment that frost is deposited on the walls and containers therein, causing the containers to stick and preventing easy removal thereof. The air circulation also carries food odors into the compartment to contaminate the water or delicate confections being frozen with unpalatable foreign flavors. It has been heretofore proposed to use a door over the end of the compartment, but even that is insufficient to prevent deposition of frost 15 around the mouth of the compartment, due to the extreme low temperatures maintained therein which serve to condense the moisture in the air attracted to the low temperature area. I have discovered that it requires the provision 20 of a highly efficient air seal to eliminate condensation and frosting so that it is an object of this invention to provide such a seal.

It is another object of this invention to provide 25 an air seal or gasket that can be applied to the shell of the quick freezing compartment and that will be yieldingly interposed between the end of the shell and a spring closed door.

It is a further object of this invention to provide 30 an elastic gasket engaging both the periphery and edge of an open ended compartment whereby to maintain the gasket in position.

It is another object of this invention to provide 35 a means for sealing the freezer compartment of a refrigerator from the food storage compartment, independent of operation of the door for said food storage compartment.

Other and further important objects of this invention will be apparent from the disclosures in the specification and the accompanying drawing.

40 This invention (in a preferred form) is illustrated in the drawing and hereinafter more fully described.

In the drawing:

45 Fig. 1 is a fragmentary front view of an open refrigerator showing the shield and door covering the freezing unit and ice tray receptacle or sleeve;

50 Fig. 2 is a fragmentary perspective view of the front end of the freezer sleeve with a gasket ap-

plied thereto embodying one form of this invention;

Fig. 3 is an enlarged section on the line 3—3 of Fig. 2, adding the door thereto; and

Fig. 4 is a section similar to Fig. 3, embodying 5 a modified form of gasket.

As shown on the drawing:

The top portion of an opened refrigerator compartment 10 is shown in Fig. 1 to illustrate the location of a freezer unit behind a shield 11 apertured for entry to the open end of a freezer sleeve 12 into which trays are inserted to produce ice cubes or frozen confections. The shield aperture is closed by a door 13 normally held shut by spring hinges 14.

15 The freezer sleeve 12 is formed as rectangular in section to accommodate a stack of ice trays and may be slightly enlarged to form a shoulder 15 back of the open end 16 to facilitate access to and removal of selected trays. It may also be advantageous to roll back the edge of the entrance end as shown at 17 in Fig. 3, although if desired, the end may be arranged otherwise as, for example, flared as at 18 in Fig. 4.

20 An endless gasket ring of resilient or elastic material 19 is shaped to conform to the profile of the enlarged part of the shell, with a front bead portion 20 overlapping the edge of the opening and a rear portion 21 seating behind the shoulder formed by the enlarged part of the shell. 25 The ring is stretched to snap over the shell, the stretching causing a tension in cross section which causes the front and rear portions to snugly fit the corresponding parts of the shell to retain the gasket in place, the front bead 20 serving 30 as a bumper and seal against the inner surface of the door. It is desirable to slightly undercut the front bead to form a reentrant inner surface 22 for the lip 23 of the bumper.

35 While I have described the preferred form of 40 gasket shown in Fig. 3 as made of resilient or elastic material, I desire to have it understood that I do not desire to limit myself to the use of solid live rubber, since other materials may be utilized to support the front bead forming the 45 bumper and gasket seal.

A modified form of gasket construction as 50 shown in Fig. 4 comprises a bead 24 adapted to engage over the flared end of the shell, an inner clip 25 holding the bead in place.

55 It will thus be seen that I have invented an improved closure sealing gasket particularly adapted for use in sealing the quick freezing compartment from contaminating air circulation and in the prevention of frosting and sticking 55

of the trays inserted therein, my sealing gasket being adapted to retain its effective position without interfering with the insertion or removal of the trays.

5. The cabinet 10 is provided with a door 30 for closing the food storage compartment, and which door operates independently of the freezer compartment closure member 13.

10 While several specific embodiments of my invention have been illustrated and described, it must be appreciated that many modifications may be made in the construction thereof without departing from the scope of the invention, and for that reason I do not desire to be limited 15 to any particular form or arrangement except in so far as such limitations are included in the following claims.

I claim:

1. The combination with a freezer compartment formed by a compartment member provided with an access opening and a closure member spaced from said compartment member but cooperating with said compartment member to close said access opening, of a yielding sealing 20 element supported by one of said members and engageable with the other of said members so as to be positioned between said members around the periphery of said access opening to prevent the entrance of air into said compartment member and retard transmission of cold from said compartment member to said closure member, a heat insulated compartment surrounding said compartment and closure members, said insulated compartment having a door opening rendering said closure and compartment members accessible, and a door for said insulated compartment operable independently of said closure member.

2. The combination with a freezer compartment 40 formed by a sleeve member having an open end to provide an access opening, and a closure member spaced from the open end of said sleeve mem-

ber but cooperating with said sleeve member to close said access opening, of a resilient sealing strip embracing the periphery of the open end of said sleeve member and projecting into engagement with said closure member so as to be 5 positioned between said members to prevent the entrance of air into said sleeve member and retard transmission of cold from said sleeve member to said closure member, a heat insulated compartment surrounding said sleeve and closure 10 members, said insulated compartment having a door opening rendering said closure and sleeve members accessible, and a door for said insulated compartment operable independently of said closure member.

15 3. The combination with a freezer compartment formed by a sleeve member provided with an access opening, and a closure member spaced from said sleeve member but cooperating with said sleeve member to close said access opening, 20 of a yieldable sealing element supported by one of said members and engageable with the other of said members so as to be positioned between said members around the periphery of said access opening to prevent the entrance of air into 25 said sleeve member and retard transmission of cold from said sleeve member to said closure member, a heat insulated compartment surrounding said sleeve member and provided with a door opening rendering said closure member 30 accessible, a shield adjacent said door opening and said sleeve member, said shield having an opening adjacent said access opening to render said sleeve member accessible and being spaced from said sleeve member, said closure member 35 being pivotally supported by said shield to provide for closing the opening in said shield when positioned to close said access opening, and a door for said insulated compartment operable independently of said closure member.

40 LEONARD H. DARBYSHIRE.
